UNITED STATES PATENT OFFICE.

FRANK J. HASSELL, OF DALLAS, TEXAS, AND ROY S. CUNNINGHAM, OF ST. LOUIS, MISSOURI.

BREAD-CUTTER.

No. 870,626.

Specification of Letters Patent.

Patented Nov. 12, 1907.

Application filed April 18, 1907. Serial No. 368,920.

To all whom it may concern:

Be it known that we, FRANK J. HASSELL and Roy S. CUNNINGHAM, citizens of the United States, residing respectively at Dallas, county of Dallas, State of Texas, and in St. Louis, State of Missouri, have invented certain new and useful Improvements in Bread-Cutters, of which the following is a full, clear, and exact description, reference being had to the accompanying drawings, forming a part hereof.

10 Our invention has relation to improvements in bread-cutters; and it consists in the novel construction and arrangement of parts more fully set forth in the specification and pointed out in the claims.

In the drawings, Figure 1 is a side elevation of the 15 cutter; Fig. 2 is a top plan thereof; and Fig. 3 is a vertical cross section on the line 3—3 of Fig. 1.

The object of our invention is to construct a bread-cutter which is capable of operating upon successive loaves of bread, the machine being provided with 20 means for first trimming off the crust on the sides of the loaf.

A further object is to provide means for picking up a batch of the severed sections or slices all as will herein more fully appear from a detailed description 25 of the invention which is as follows:

Referring to the drawings, F, represents a frame or table having an inclined top, the side members of which are provided with longitudinal grooves 1, 1, for receiving the tongues 2 of a sliding grating or feed-frame 3. Secured to the feed-frame 3 is a grated abutment 4 against which the bread loaves B are placed. Mounted transversely of the frame F is an operating shaft S having a crank-disk 5 at one end and a balance wheel 6 at the other end, the shaft being provided with 30 a series of cutter-disks or blades 7 having a sinuous cutting edge for the cutting of the loaves. The slide or feed-frame 3 has a lateral platform or extension 3' terminating in an abutment 4', for the support of a loaf longitudinally, such loaf being first introduced between the outer blade 7' adjustably keyed to the shaft 40 S, and the first blade 7 of the inner series, these two

blades trimming the crust off the sides of the loaf. The position of the blade 7' on the shaft is determined of course by the thickness of the loaf, and it is made adjustable to accommodate different sizes of loaves. 45 When once adjusted it is clamped into position by the binding screw 8. The loaves with their sides thus trimmed, are arranged on the slide 3 in front of the abutment 4, and the slide pushed downward and forward; the operator with one hand turning the shaft 50 and blades and cutting the bread into slices. At the lower end of the frame F, is a rod 9 mounted between the brackets 10, and over the rod 9 are loosely mounted the yielding prongs or members 11 between whose free outwardly flaring ends the cut slices pass. By seizing 55 the prongs and compressing them against the opposite ends of the assembled sections or slices thus advanced, the entire series may be picked up as by a pair of tongs, and disposed of in any manner.

Having described our invention what we claim is: 60

1. A bread cutter comprising a supporting frame, a slide or feed-frame mounted thereon, an abutment on the slide against which the bread loaves may bear, a transverse shaft having a series of cutter disks, a lateral extension or platform formed on the slide for supporting a loaf longitudinally, a terminal adjustable blade on the shaft between which and the first blade of the inner series said loaf can be inserted and its sides trimmed, the parts operating substantially as set forth. 65

2. A bread cutter comprising a supporting frame, a slide or feed-frame, means for supporting bread loaves on said slide both transversely and longitudinally, means for trimming the loaves when supported in their longitudinal positions, and for slicing them while occupying a transverse position across the frame, and means mounted with 70 frame for seizing the slices collectively at the conclusion of the cutting operation, substantially as set forth. 75

In testimony whereof we affix our signatures, in presence of two witnesses.

FRANK J. HASSELL.
ROY S. CUNNINGHAM.
